PREFABRICATED BUILDING

Dave Chapman, Chicago, Ill., assignor to Panelfab Products, Inc., North Miami, Fla., a corporation of Florida

Filed July 2, 1963, Ser. No. 75,623

Term of patent 14 years

(Cl. D13—1)

FIG. 1 is a perspective view of the building as seen from above looking at the front.

FIG. 2 is a sectional view taken substantially on lines 2-2 of FIG. 1, and illustrating the floor plan of the building.

FIG. 3 is a front elevational view of the building.

FIG. 4 is a rear elevational view of the building; and

FIG. 5 is an end elevational view of the building looking toward the left at FIG. 3.

The dominant features of my design reside in the portions shown in full lines on the drawings.

I claim:

The ornamental design for a prefabricated building, substantially as shown and described.
